UNITED STATES PATENT OFFICE.

FREDERICK FISHER, OF MARLBORO, MICHIGAN.

INTERNAL-COMBUSTION ENGINE.

1,102,400.

Specification of Letters Patent.

Patented July 7, 1914.

Application filed May 7, 1906. Serial No. 315,481.

To all whom it may concern:

Be it known that I, FREDERICK FISHER, citizen of the United States, residing at Marlboro, in the county of Lake and State of Michigan, have invented a certain new and useful Improvement in Internal-Combustion Engines, (Case 1,) of which the following is a full, clear, concise, and exact description, reference being had to the accompanying drawings, forming a part of this specification.

In the ideal Otto cycle the gas (not necessarily fuel) which is the agent for the transformation of energy, is heated at constant volume, the pressure being correspondingly increased. In the Carnot cycle and the ideal cycle of the Diesel motor the heating takes place at constant temperature, that is, during the supply of heat to the gas, expansion takes place of such a character that the temperature of the gas is maintained constant. As distinguished from a great variety of mechanisms intended to carry out these cycles of the prior art, my invention provides for the use of a cycle which more or less closely approaches the ideal of heating at constant pressure. Practical limitations and considerations are such that neither the ideal Otto cycle, nor the ideal Carnot cycle, nor the ideal cycle of the Diesel motor are attained in practice. Neither is it essential that the ideal condition of constant pressure during heating should be fully attained in order to make use of my invention. But a recognition of the ideal cycle which is utilized in the practice of my invention will enable those skilled in the art to make wide modifications and changes without sacrificing the fundamental advantages which my invention is adapted to secure.

My invention contemplates the use of reciprocating mechanism in conjunction with which power is intermittently developed, as, for example, in a combustion chamber associated with a cylinder and reciprocating piston. Heating of the gaseous agent of transformation takes place periodically, due to the combustion of a suitable fuel in air or other combustion supporting medium. Consequently there will be corresponding changes in the pressure and temperature unless means is provided for increasing the volume during the periods of combustion whereby the pressure may be maintained constant, or as nearly constant as practical limitations and requirements may dictate.

To this end my invention contemplates the association of a reservoir with the combustion chamber. In order to carry out the ideal condition of absolutely constant pressure during heating, this reservoir is constantly under a stress equivalent to the pressure at which heating is to begin. The reservoir is adapted to receive and store energy whenever the pressure in the combustion chamber tends to rise above the predetermined maximum limit, this energy being returned to the combustion chamber whenever the pressure therein falls below the pressure at which heating occurs and which corresponds with the stress in the reservoir.

I shall describe certain modifications of my invention, and after referring broadly to some of the advantages to be secured, shall designate in the appended claims the limitations and scope of the invention which I seek to protect.

In the accompanying drawings Figure 1 is a plan view of an engine embodying my invention; Fig. 2 is a cross-sectional view thereof, taken on line 2-2 of Fig. 1; Fig. 3 is an end elevation, parts being shown in cross-section; Fig. 4 is a diagrammatic view showing the application of my invention to so-called two-cycle engines, and Fig. 5 is a longitudinal cross-sectional view of a lighter and smaller type of engine than that shown in the other figures.

In Figs. 1, 2 and 3 I have illustrated the preferred form of my invention, in which like characters of reference apply to like parts. At 11 there is an engine cylinder in which the plunger piston 12 reciprocates. The motion of the piston is transmitted by means of the connecting rod 13, the crank pin 14 and the crank 15 to the main shaft 16, upon which the flywheel 17 is mounted, these parts constituting the well-known transmission gear of reciprocating engines. The rear end of the working cylinder communicates directly with the lower end of a combustion chamber 18. As indicated in the drawings, the combustion chamber is filled to a greater or less extent with water or other suitable liquid which comes directly in contact with the rear end of the piston 12. At 19 there is an energy storing reservoir, there being a passage way 20 leading from the interior of the reservoir to the combustion chamber, this passage way being controlled by the float ball valve 21, which constitutes a check valve, the operation and

function of which will more fully appear. Suitable valve mechanism serves to admit periodically a charge of fuel and a combustion supporting medium to the upper end of the combustion chamber. Thus, for instance, in this preferred embodiment of my invention, I have shown an inlet valve 22 arranged to admit, at proper intervals, a combustible mixture, such, for instance, as air and any of the well-known hydro-carbons used in internal combustion engines. A spring 23 tends to maintain the valve 22 in place upon the seat formed in the lower part of the valve casing 24. The exhaust port 25 is equipped with an exhaust valve 26, and a cam 27 and actuating lever 28 and a connecting rod 29 serve to actuate the exhaust valve by way of the toggle joint 30, the lower member of the toggle joint being pivoted at 31 to the top of the valve casing 24, and at 32 to the stem 33 of the exhaust valve 26. The operation of this embodiment of my invention may be described as follows: Assuming the engine to have been put in motion in any suitable manner, we may start with a consideration of the forward movement of the piston 12 within its cylinder 11. As the piston sweeps through the cylinder a corresponding volume of water will be drawn from the lower part of the combustion chamber to follow up the piston. This withdrawal of the water from the lower part of the combustion chamber will cause the level of the water in the combustion chamber to fall, tending to create a vacuum in the upper part of the combustion chamber. The suction causes the admission of a suitable charge of the combustible mixture through the inlet valve 22. The upper part of the reservoir 19 is filled with a compressed gas; such, for instance, as air, which has been forced into the reservoir through the opening 35, this opening being fitted with the check valve 36 and a plug 37 to prevent leakage. The air in the reservoir is compressed to a high degree; such, for example, as three or four hundred pounds per square inch, and it is the degree of this initial and constant stress in the storage reservoir which determines the substantially constant pressure at which the heating of the working gas occurs. During the admission stroke of the piston the pressure in the reservoir serves simply to maintain the ball valve 21 upon its seat, thus effectively closing the passage way between the reservoir and the combustion chamber and preventing any change in the potential energy stored in the reservoir. The momentum of the flywheel causes a return or rearward stroke of the piston within its cylinder. The expulsion of the water from the rear end of the cylinder into the combustion chamber causes a compression of the combustible mixture in the top of the combustion chamber, both the in-

let and the exhaust valves being closed during this stroke. By varying the speed of the engine and the disposition and the proportion of parts in a manner well understood by those skilled in the art; it is possible to secure an approximation of true adiabatic compression sufficient for the purposes of ignition. If the compression of the working gas is relied upon to increase the temperature sufficiently for the purpose of self-ignition, the initial stress or potential in the storage reservoir should be so adjusted that the closure of the check valve 21 will be maintained until after the ignition of the combustible. If combustion is caused by the substantially adiabatic compression of the working gas, the combustion will be practically instantaneous in all parts of the mixture as distinguished from combustion started from a given point by an electric spark or otherwise and which is thereafter propagated throughout the mixture. The combustion of the fuel immediately increases the energy of the working gas, tending to cause an increase in pressure or volume. The pressure will rise slightly to a degree equivalent to the potential maintained in the storage reservoir, when the preponderance of pressure in the combustion chamber will raise the check valve 21 from its seat, causing a flow of water from the combustion chamber into the lower part of the compression reservoir whereby an equalization of pressure in the reservoir and combustion chamber is maintained and whereby the heating of the working gas takes place at a pressure approximating a constant value to a degree dependent upon the size and precise construction of the storage reservoir. In order that there may be comparatively little resistance tending to prevent the equalization of the pressure in the combustion chamber, it is desirable to make the opening between the combustion chamber and the storage reservoir of very large dimensions. The heat of combustion will result principally in an increase in volume of the working gas. The compression reservoir acts as a spring or weight acting against gravity, to absorb the power suddenly developed by the explosion of the combustible mixture. The flow of water into the lower part of the compression reservoir floats the valve 21 clear of its seat 20, and the influx of water serves to float the valve and maintain an operative communication or association of the pressure reservoir with the combustion chamber whenever the pressure in the combustion chamber exceeds the normal pressure in the reservoir. Although the ignition of the combustible may occur shortly before the dead center is reached, there is no greatly increased pressure upon the piston and the momentum of the flywheel is sufficient to carry the engine easily over the dead center.

130

After the engine has passed over the dead center, the piston commences its travel toward the front end of the cylinder. During this stroke, the working gas experiences an adiabatic expansion, the increase in volume of the gas being accompanied by a diminishing pressure. The expansion of the air in the storage reservoir, acting like a spring under stress, returns to the combustion chamber an amount of energy approximately equal to that stored in the reservoir during the rapid heating of the working gas. When the potential energy in the reservoir has diminished to its normal value sufficient water will have been expelled from the lower part of the compression reservoir to permit the valve 21 to seat itself, thereby closing the passage way between the combustion chamber and the storage reservoir, whereby the condition of the stress in the reservoir is maintained and whereupon the power delivered to the moving piston will be derived wholly from the continued expansion of the working gas in the combustion chamber and not in part from the energy stored in the reservoir, as during the first part of the stroke. The expansion of the working gas in this embodiment of my invention acts upon the moving piston through the agency of the water which fills the lower part of the combustion chamber. When the piston has reached the forward end of its stroke, the cam 27 which is operated by a suitable shaft 40 connected by gearing 41 with the main shaft, actuates the valve gearing connected with the exhaust valve 26, whereby the valve 26 is depressed to permit the expulsion of the gases of combustion during the succeeding rearward movement of the piston, this movement being caused by the momentum of the flywheel. This completes one cycle of operations, and the succeeding cycle commences, as before, with the admission of the working gas and fuel succeeded by its compression, ignition, heating, expansion and exhaust. The flywheel is so related to the speed of operation that its momentum will maintain a substantially uniform rate of rotation.

At 42 I have shown a water inlet associated with the check valve 43 which permits the influx of water under a slight pressure from a suitable source of supply, through the supply pipe 44. Whenever the valve is depressed by the plunger 45 connected with the eccentric 46 upon the cam shaft 40 the eccentric causes a small quantity of water to be admitted to the combustion chamber 18, this admission of water taking place during the aspirating stroke or the exhaust stroke, or both, and serving to replace any water that may have been evaporated by the hot gases or the heat retained in the walls of the combustion chamber and the slight excess of water which passes out through the

opening at the top of the combustion chamber serves to flush the valve and valve seat to prevent its fouling.

The mode of operation which I have thus far described is independent of the precise nature of the combustible mixture admitted to the combustion chamber. An engine of this type can be designed to utilize any of the fuels now used in internal combustion engines; such, for instance, as liquid or gaseous hydro-carbons, blast furnace gas, producer gas, or even solid fuel, under suitable conditions of operation. My invention provides means whereby foul or impure combustible mixtures may be used to advantage, because the gases of combustion do not come into contact with any of the moving parts except the inlet or exhaust valves either before or after ignition. Furthermore, the scavenging of the combustion chamber is complete with every full cycle of operation, because the rising level of the water in the combustion chamber expels the last trace of the waste gas of combustion from the top of the combustion chamber. The water serves also to scour the valve and valve seats. The constant passage of water through the combustion chamber serves to remove any abrasive solids from the combustion chamber, thereby preventing the wear upon the cylinder and piston which is one of the greatest difficulties heretofore encountered in attempts to utilize cheap fuels in internal combustion engines. On account of the very high compression of the combustible mixture before ignition, my invention provides a means particularly well adapted for the use of poor mixtures. When, as in this embodiment of my invention, it is desired to operate the valve which controls the passage way between the reservoir and combustion chamber automatically by the variations of pressure in the combustion chamber it is, of course, impossible to secure heating at an absolutely constant pressure of the working gas, but the pressure is practically constant as compared with the pressure which would result from the explosion of a mixture compressed to the temperature of ignition if the gas were restricted to constant volume, as in the internal combustion engines employing the well-known Otto cycle. Furthermore, the degree to which the pressure during heating approximates a constant value may be controlled by the design of the storage reservoir. If the storage reservoir takes the form of an air compression chamber, as in the preferred embodiment of my invention, an increase in the size of the compression chamber will decrease the rise in pressure in the combustion chamber upon the ignition of the combustible mixture.

In my description of this invention I have in mind the broadest meaning of the term

"storage reservoir" and contemplate the use of any elastic medium whose stress may be varied due to an increase in the energy of the working gas in the combustion chamber, or 5 the use of any mechanism or medium whose potential energy may be increased by the expansion of the working gas. My invention 10 contemplates the conservation of the energy charged into the storage reservoir during heating of the working gas and the subsequent transformation of this energy in delivering power to the flywheel of the engine. The water within the combustion chamber of this preferred form of my invention 15 serves not only to transmit power to the piston but also to maintain the combustion chamber and the valve mechanism at a safely low working temperature, the replacement of the water being sufficiently rapid to cause 20 effective cooling.

While I do not limit the embodiments of my invention to any particular means for igniting the combustible mixture, the self-ignition of the combustible by the compression 25 of the working gas is simple and effective, and the presence of the storage reservoir prevents any harmful effects, even in case of pre-ignition. It is now well settled that the efficiency of an internal combustion 30 engine depends very largely upon the degree of compression to which the working gas is subjected before heating, and my invention provides a means for securing a very high degree of compression without any 35 harmful consequences. The high mean effective pressure in the cylinder gives an engine of large capacity.

An engine of my invention permits of inexpensive construction as compared with 40 engines in which the working gas comes directly into contact with the working cylinder and piston because, in an engine of my invention, water is the medium which must be confined by the moving joints, and it is very 45 much easier and cheaper to pack a joint to prevent leakage of water than it is to pack a joint to prevent leakage of gas under high pressure and temperature. The valve mechanism required to admit the working gas and 50 fuel and to convey the waste gases of combustion from the combustion chamber may be very simply constructed in an engine of my invention. The principal difficulties 55 which are encountered in the proper lubrication of internal combustion engines, particularly those of high efficiency, are done away with in an engine of my invention on account of the low temperature at which the moving parts are operated. The capacity of 60 internal combustion engines as heretofore constructed has been very much limited on account of the difficulties encountered in properly cooling the working parts of an engine in which there is a large free space in 65 which the combustible mixture is ignited.

My invention obviates this difficulty on account of the inherently low temperature of operation and on account of the inherent cooling due to the continuous passage of water through the interior of the combustion 70 chamber.

In conjunction with this preferred form of my invention I have illustrated mechanism for pulverizing coal or other solid substance and utilizing it as a fuel for the engine. The coal is fed to pulverizing apparatus from a suitable hopper 47. It passes through the opening 48 to the interior of the grinding ring 49, where it is ground by two or more balls 50, 50, which are driven by a 75 boss 51 keyed to the main shaft 16. The inlet pipe 52 leads from the pulverizer to the casing of the inlet valve 22. The suction which causes the depression of the inlet valve produces a draft of air which enters 80 through the opening 53 surrounding the main shaft and passes through the interior of the grinding ring 49 and thence through the inlet pipe 52 to the casing of the inlet valve 22. The air in passing through the 85 pulverizing mechanism picks up a cloud of pulverized coal and carries it to the inlet valve where it is admitted at proper intervals to the combustion chamber 18. I have indicated, furthermore, a governor for controlling the speed of the engine by throttling the admission of the combustible mixture to the combustion chamber. This governor in simplified diagram, comprises a collar 54 mounted upon the main shaft and to which 90 the governor weights 55, 55, are pivoted. The outward movement of the governor weights, due to centrifugal force, tends to move the sleeve 56 against the compression of a governor spring 57. A flange 58 forming 95 a part of the sleeve 56 serves to close the opening 53 to a greater or less extent, depending upon the position of the governor weights, which in turn are controlled by the speed of rotation of the engine. It will be 100 readily understood by those skilled in the art that other devices of suitable nature may be adapted to my improved engine for the supply of combustible mixtures of other kinds. The pressure of the air confined in 105 the compression reservoir may be adjusted 110 to correspond with the nature of the fuel and other conditions of operation.

I have indicated at 58' a valve which is used for cleaning out the interior of the 115 engine.

In Fig. 4 I have diagrammatically illustrated a modification of my invention, which I prefer to call a two-cycle engine. Its principles of operation do not differ broadly 120 from those already described in connection with the four-cycle type of engine. The center of the main shaft in the two-cycle type of Fig. 4 is indicated at 60. A crank extends from the main shaft to the crank pin, 125 130

the center of which is indicated at 61. The connecting rod is indicated by the dotted line 62, extending from the crank pin 61 to the wrist pin 62', this wrist-pin being carried in the plunger piston 63, also indicated in dotted lines. The cylinder of the engine is shown at 64, and as in the four-cycle type of machine, this cylinder is open at its rear end and communicates directly with the combustion chamber 65. A floating ball valve 68 controls the opening through a passage way 67 from the compression reservoir 66 to the combustion chamber 65. In order that the exhaust channel 69 may lead from the bottom of the combustion chamber to a point 70 near the top of the combustion chamber the center of this combustion chamber 65 is offset with respect to the cylinder 64. At 71 I have indicated a ball valve controlling the opening from the exhaust channel 69 to the exhaust pipe 72. The inlet check valve 73 controls communication from the inlet pipe 74 to the interior of the combustion chamber. At 75 I have indicated an auxiliary compressor cylinder having a piston 76 actuated by the connecting rod 77 which in turn is driven by the crank pin 61.

In operation this embodiment of my invention may be described as follows: We may assume that the crank-pin 61 is already in rotation in the direction of the arrow 78 about the center of rotation 60. This being the case, the piston 76 of the compressor cylinder will commence its stroke from the bottom of the cylinder, sucking in a charge of air through the check valve 79 and the air pipe 80. Upon the reverse stroke of the piston 76 this air will be compressed to a moderate degree, for example, to three or four atmospheres. After this compression has continued to some degree, the auxiliary scouring valve 81 is opened by a cam 82 mounted upon the cam shaft 83, which in turn is geared at 84 to the main shaft of the engine. The opening of this scouring valve permits a small amount of air to pass from the lower end of the compressor cylinder through the inlet pipe 84', and the main inlet check valve 73 to the interior of the combustion chamber 65. This combustion chamber, as in the case of the four-cycle engine already described, contains a volume of water sufficient for the purposes of operation, to be hereinafter described. At the time when the scouring valve 81 is opened, the exhaust valve 71 will also be in an open condition, due to proper actuation by means of the cam 85. The air blowing in through the inlet check valve 73 will scour the interior of the combustion chamber of all residue which may be left from a previous explosion. The cam 85 permits the exhaust valve 71 to seat itself, thus preventing the continued escape of gases or water

from the interior of the combustion chamber. The cam 86 then actuates the main inlet valve 87, which permits the balance of the air which has been compressed in the auxiliary compressor cylinder to flow through the inlet pipe 74 to the interior of the combustion chamber 65. I have indicated in this drawing a means for utilizing powdered coal as a fuel. This consists essentially in a hopper 88 in which the powdered coal is placed and from which it is periodically introduced into the inlet pipe in definitely measured quantities. This measured introduction of the powdered fuel is accomplished by means of a sliding plunger 90 actuated by a connecting rod, indicated by the dotted line 91, this connecting rod leading to an eccentric 92 whose eccentricity is controlled by the inertia governor 93, the eccentric being pivoted at 94. The reciprocation of the plunger 90 causes a small quantity of powdered coal to be forced through the supply pipe 95 and deposited within the inlet pipe 84', as indicated at 96. The compressed air passing rapidly through the inlet valve 87 picks up this charge of finely powdered coal and carries it into the top of the combustion chamber, at the same time thoroughly distributing it through the charge of air which is admitted at the same time. The combustible mixture having thus been introduced into the upper part of the combustion chamber the continued movement of the piston 63 causes the level of the water in the combustion chamber to rise and produce a compression of the mixture in the top of the chamber. The consequent rise in temperature eventually causes ignition and explosion of the mixture. As in the case of the four-cycle type of engine, the operative connection which is then established between the storage reservoir and the combustion chamber prevents the enormous rise in pressure which would otherwise take place due to this high degree of compression before ignition. Upon the ignition of the mixture the tendency to increase the pressure in the combustion chamber causes the floating valve 68 to be raised from its seat, thus permitting an influx of water from the combustion chamber to the storage reservoir, the stress or compression of the air in the compression reservoir being increased by an amount depending upon the relative proportions of the combustion chamber and the other parts of the engine. This storage of energy in the compression reservoir serves to equalize the pressure in the reservoir and combustion chamber whereupon the outward movement of the piston commences under pressure substantially equal to that of the air in the compression reservoir and continuing until the pressure has been so far reduced as to cause the expulsion of some of the water from the

compression reservoir which permits the floating valve 68 to seat itself, the seating of this valve when the pressure in the storage reservoir has reached its normal value 5 breaks the operative association of the compression reservoir with the combustion chamber, whereupon it is the continued adiabatic expansion of the working gas in the combustion chamber alone which continues the power stroke of the piston. At 10 the end of the forward stroke of the piston 63 the exhaust valve 71 is opened by its cam 85, and the return stroke of the piston forcing the water from the cylinder 64 into 15 the lower part of the combustion chamber, drives the exhaust gases of combustion from the top of the chamber through the exhaust channel 69 and the exhaust valve 71 to the exhaust pipe 72. During this part of the cycle, during which the pressure in the combustion chamber is very low, water flows into same through check valve 98 from supply pipe 99, supplying the water needed to replace that evaporated and to scour the valves. 20 The excess water travels from the combustion chamber into the top of the exhaust channel and is expelled through the exhaust pipe. As previously explained, the scouring valve 81 will again be opened shortly 25 before the exhaust valve 71 is closed so as to insure the expulsion of any residue of exhaust gases of combustion before the influx of the succeeding charge of air and fuel. Shortly before the main piston 63 reaches 30 the end of its backward stroke, the auxiliary compressor piston 76 will have accumulated another charge of compressed air which will be blown into the combustion chamber with its quota of fuel, whereupon the above 35 described cycle of operation will be repeated indefinitely. The slide valve 100 is connected with the end of the measuring plunger 90 and controls the opening of the pipe 80 to the atmosphere. During the instroke 40 of the piston 63, the exhaust valve 71 is held in its open position by the operation of the cam 85 on the shaft 83 until the piston 76 has nearly or quite completed its instroke. During this interval the valves 81 45 and 87 are closed and air is compressed in the pipe 80 to a certain degree, say three or four atmospheres. During this interval the gases of combustion are partially expelled from the combustion chamber 65 by 50 the water being forced upward in said chamber by the inwardly moving piston 63 and when this piston 63 has reached substantially the position shown in Fig. 4, the valve 81 is opened for a brief interval to permit 55 a part of the compressed air in the pipe 80 to flow through the check valve 73 into the combustion chamber 65 and out through the pipe 69 and the exhaust valve 71, carrying with it the remaining products of combustion 60 and a part of the water from the

upper portion of the combustion chamber to complete the scavenging of the same. Then, with the piston 76 still in substantially its innermost position, the shaft 83 has rotated the valve cams 82, 85 and 86 70 sufficiently to permit the exhaust valve 71 to rest upon its seat and the valve spring to close the scouring valve 81 and to open the main intake valve 87. The compressed air remaining in the pipe 80 now rushes rapidly through the pipe 74 carrying with it the powdered fuel 96 through the check valve 73 into the upper portion of the combustion chamber 65, since the pressure in the said chamber was practically atmospheric at the instant of opening the valve 87. Equalization between the pressure in the pipe 80 and the combustion chamber 65 at once takes place and a decrease in pressure in the combustion chamber is prevented by the closed 75 exhaust valve 71 and the check valve 73. The fuel mixture at this time is under a low pressure, say two atmospheres in the combustion chamber, which pressure is not sufficient to spontaneously ignite the charge. 80 The piston 63 now completes its inward stroke and compresses the charge of fuel and air mixture to a very high degree owing to the conical shape of the upper portion of the combustion chamber, and the fuel 85 is ignited by the high temperature developed. The pressure thereby produced is communicated to the piston 63 and the pressure relief chamber and the cycle of operation described above is repeated indefinitely. 90 This modification of my invention, like that illustrated in Figs. 1, 2 and 3, may be adapted by those skilled in the art to burn other fuel than powdered coal. The advantages heretofore pointed out in connection with 95 the four-cycle type of engine are present in the modification illustrated in Fig. 4, the latter form having such other advantages as are secured in engines having a power stroke for every revolution of the fly-wheel. 100 In Fig. 5 I have illustrated still another modification of my invention, the essential principles of operation being the same as those inherent to the embodiments heretofore described, one of the principal differences being that the storage reservoir is incorporated into the main piston of the engine. The engine shown in this Fig. 5 is of the four-cycle type. I have shown a main cylinder 110 in which the piston 111 115 reciprocates. The center of the main shaft is at 112 and the motion of the piston is transmitted to this shaft through the connecting rod 113 and the crank 114. The piston is made hollow as shown and thus 120 provides the storage reservoir. The ring 115 clamps to the top of the piston a diaphragm 116 of rubber or other flexible material of like nature. A metal button 117 covers the top of the diaphragm and is pre- 125 130

vented from rising above this particular position by the overhanging lip 118 of the ring 115. The purpose of this construction will more particularly appear hereinafter. The 5 combustion chamber in this modification of my invention is incorporated into the top of the cylinder, and as indicated in the drawing, the cylinder at its upper end is given a spherical or parabolic form in order 10 to reduce, as far as possible, the surface exposed to the hot gases of combustion. This feature I deem to be particularly useful in engines of smaller size, where the area exposed to the hot gases of combustion bears 15 a large ratio to the volume thereof. A valve mechanism adapted to this modification of my invention is indicated in the drawing. It comprises a poppet valve 119, an inlet valve 120 and an exhaust check valve 121. 20 I have not shown the mechanism for actuating these valves, but any suitable valve gear may be adapted by those skilled in the art.

In operation this embodiment of my invention is as follows: The application of power from an external source or the inertia of the flywheel causes a downward movement of the piston 111 from the position shown in the drawing during which stroke both the inlet valve 120 and the poppet valve 119 are opened to permit a charge of an explosive mixture to be drawn in through the inlet pipe 122. This combustible mixture fills the upper part of the cylinder 25 whereupon the valves 119 and 120 are closed and the upward stroke of the piston and its compression of the mixture in the upper part of the cylinder. This compression may be continued, as in the other modifications of my invention, until the temperature of the mixture rises to a point at which it ignites in all parts simultaneously, causing a sudden increase in volume, the increase in volume being accommodated by a downward movement of the button 117 and the associated diaphragma 116, the force of the working gas being transmitted by means of the water which fills the combustion chamber as in the other embodiments of my invention heretofore. At the conclusion of the downward stroke a suitable valve mechanism causes the poppet valve 119 to be pressed downward, thus allowing the exhaust gases in the combustion chamber to escape through the exhaust check valve 121 during the succeeding upward stroke of the piston. The hot gases of combustion on their way to the outlet 124 pass through the heating jacket 123 which surrounds the upper part of the combustion chamber. The exhaust gases of combustion therefore assist in maintaining a high temperature of the combustion chamber. The poppet valve 119 is not permitted to close at the end of 60 the exhaust stroke of the piston but is held

down during the aspirating stroke which immediately follows. During the power stroke, the expansion of the compressed air in the storage reservoir takes place until the button strikes the stop at the end of the 50 piston, the remainder of the stroke being accompanied by the expansion of the gases in the combustion chamber alone. The aspiration and compression, the storage reservoir is at this time, not much like that 55 of a water spring, placed under compression and so carried at the maximum pressure. The aspiration is discontinued, as shown, around the upper part of the cylinder 60 by a water supply pipe 125 leading to the cylinder, passing through a check valve 127 in the cylinder sleeve and thence along the side of the upper part of the piston, into the combustion chamber, which is, in view, the upper part of the engine cylinder, supplying the water necessary for scouring purposes, and to replace that evaporated. The excess water passes out through the poppet valve and the exhaust check valve, serving to keep them clean.

While I have herein shown and described certain modifications of my invention, it will be apparent to those skilled in the art that numerous modifications may be made without departing from the spirit thereof and I do now, therefore, wish to be limited by the precise construction herein shown and described, that.

Having set forth certain specific examples of my invention, I claim as new and distinct to 100 invent by Letters Patent:

1. In an internal combustion engine, the combination of a working cylinder, a reciprocating piston therein, a fly wheel and a connecting rod connecting the piston and the wheel, a combustion chamber communicating with said cylinder, an excess pressure relief chamber in communication with the combustion chamber, a liquid partially filling both chambers and subject to the action of said piston, inlet valve mechanism for admitting a combustible mixture to said combustion chamber, an exhaust valve controlling the outlet from said combustion chamber, and valve mechanism for automatically opening and maintaining communication for the flow of liquid between the two chambers whenever the pressure in the combustion chamber exceeds a predetermined maximum.

2. In an internal combustion engine, the combination of a working cylinder, a reciprocating piston therein, a fly wheel and a connecting rod mechanism for connecting the piston and fly wheel, a combustion chamber communicating with said cylinder, an excess pressure relief chamber containing gas in its upper portion and in communication with the combustion chamber, a liquid partially filling both chambers and subject 125

- to the action of said piston, inlet valve mechanism for admitting a combustible mixture to said combustion chamber during an out-stroke of the piston, such combustion chamber so conformed that the inertia of the fly wheel serves upon the succeeding in-stroke to compress the combustible mixture to the point of ignition, an exhaust valve controlling the exhaust from said combustion chamber, valve mechanism for automatically opening and maintaining communication for the flow of liquid between the two chambers whenever the pressure in the combustion chamber exceeds a predetermined limit, the parts involved in compressing the combustible mixture being proportioned to produce substantially adiabatic compression of the combustible mixture to the point of ignition.
3. In an internal combustion engine, the combination of a working cylinder, a reciprocating piston therein, a fly wheel and a connecting rod mechanism for connecting the fly wheel and piston, a combustion chamber communicating with said cylinder, an excess pressure relief chamber containing gas in its upper portion and in communication with the combustion chamber, a liquid partially filling both chambers and subject to the action of said piston, inlet valve mechanism for admitting a combustible mixture to said combustion chamber during an out-stroke of the piston, the inertia of the fly wheel serving upon the succeeding in-stroke to compress the combustible mixture to the point of ignition, an exhaust valve controlling the exhaust from said combustion chamber, valve mechanism for automatically opening and maintaining communication for the flow of liquid between the two chambers whenever the pressure in the combustion chamber exceeds a predetermined limit, the parts involved in compressing the combustible mixture being proportioned to produce substantially adiabatic compression of the combustible mixture to the point of ignition, and means for admitting fresh liquid to the chambers during each cycle of the engine, the excess liquid being ejected during the exhausting stroke of the piston.
4. In an internal combustion engine, the combination of a working cylinder, a reciprocating piston therein, a fly wheel and a connecting rod mechanism associating the fly wheel and piston, a combustion chamber communicating with said cylinder, an excess pressure relief chamber, a liquid partially filling both chambers and subject to the action of said piston, there being an opening in the bottom of the relief chamber through which the liquid may flow between the two chambers, a valve in the opening between the combustion and relief chambers, said valve being maintained in an open condition while the pressure in the relief chamber remains above a predetermined normal pressure, inlet valve mechanism for admitting a combustible mixture to the combustion chamber, an exhaust valve controlling the exhaust from the combustion chamber, the parts subjected to the pressure of compression being so formed and related as to produce a compression pressure sufficient to ignite the combustible mixture without material loss of heat.
5. In a device of the class described, the combination of a combustion chamber, means for admitting fuel and a combustion supporting medium into said combustion chamber, a cylinder having a reciprocating piston therein, a liquid in said combustion chamber for transmitting power between said combustion chamber and said piston and from said piston to said combustion chamber for compressing the mixture in the combustion chamber, an excess pressure relief chamber, there being an opening from the lower part of the relief chamber into the combustion chamber, said opening being below the level of the liquid in said combustion chamber, a float valve for closing the opening between the chambers, said valve being floated from its seat upon an influx of liquid from the combustion chamber, the valve being floated from its seat during the period of excess pressure in the combustion chamber, the pressure in said relief chamber being maintained at such a point that the return stroke of the piston may compress the combustible mixture in the combustion chamber to the point of ignition before the float valve will open to establish communication between the two chambers.
6. In an internal combustion engine, a working cylinder, a combustion chamber connected to such cylinder, a pressure relief chamber, there being a passageway between the relief and the combustion chambers, and a check valve located in said passageway and movable to different positions according to the pressures in the relief and combustion chambers for establishing free communication between said chambers in either direction above a predetermined pressure.
7. In an internal combustion engine, a working cylinder, a combustion chamber connected with such cylinder, a pressure relief chamber integral with the combustion chamber and adapted to prevent excessive pressure therein, there being a passageway between said chambers, means controlling said passageway for preventing communication between such chambers below a predetermined pressure, and a gas-admission valve for the relief chamber movable to an inoperative position by pressure in the relief chamber above a predetermined limit.
8. In an internal combustion engine, a working cylinder, a combustion chamber connected to such cylinder, a pressure re-

relief chamber, there being a passageway connecting said relief chamber with the combustion chamber, and means controlling said passageway for maintaining communication in either direction between such chambers when the pressure in either one of said chambers is above a predetermined value and for preventing communication between said chambers below such predetermined value.

79 9. In an internal combustion engine, a working cylinder, a combustion chamber connected to such cylinder, a pressure relief chamber having a communicating passage to the combustion chamber to prevent excessive pressure therein, such chambers having liquid therein, and a float valve in the pressure relief chamber adapted to close said passage.

10. In an internal combustion engine, the combination of a working cylinder, a combustion chamber connected to such cylinder, a pressure relief chamber integral with the combustion chamber, there being a connecting passage between such chambers for

conveying liquid from one chamber to the other, and a valve for controlling such passage according to the height of the liquid in the relief chamber.

11. In an internal combustion engine, the combination of a working cylinder, a reciprocating piston, a pressure chamber normally containing gas under pressure, and means for communicating energy to such gas during a part of each working stroke of the engine and extracting energy from such gas to the working cylinder during another part of each working stroke of the engine and mechanism for maintaining the pressure in the pressure chamber higher than the pressure of admission in the working cylinder.

In witness whereof, I hereunto subscribe my name this 25 day of April A. D. 1903.

FREDERICK FISHER.

Witnessed:

S. S. GARRETT,
August E. BARLEY.
